RICHARD F. DOW, OF HARTFORD, CONNECTICUT, ASSIGNOR TO THE WHITNEY MFG. CO.,
OF HARTFORD, CONNECTICUT, A CORPORATION OF CONNECTICUT

CHAIN OILING DEVICE

Application filed January 7, 1930. Serial No. 419,021.

This invention relates to a novel and improved device for oiling chains, particularly of the wide flat type, the novel features of which will be best understood from the following description and the annexed drawings, in which:

Fig. 1 is a perspective view of the invention as used with a chain.

Fig. 2 is a plan view of the device showing a fragment of the chain.

Fig. 3 is a section on the line 3—3 of Fig. 2.

Various devices have been tried for uniformly lubricating a chain of the type indicated in Fig. 1, which is relatively wide and flat. For example, it has been attempted to properly lubricate a chain of this type by means of a pipe extending transversely of the chain, and having a plurality of holes therein through which the oil may drop upon different parts of the chain. This arrangement, however, has not been satisfactory, because of unequal distribution of the oil, the oil as it flows through the pipe naturally tending to drop or flow through the first hole to which it comes. Other devices have been found defective or uneconomical, and it is the object of my invention to provide a device which is not only capable of properly and efficiently lubricating a chain, but which may also be easily manufactured and applied to existing structures.

In Fig. 1, I have indicated a sprocket 1 adapted to mesh with teeth of a chain 2, which may be of the type known as "silent", this chain, for example, being composed of a plurality of links, one of which is indicated at 3. The exact details of the chain itself are not a necessary part of this invention and have consequently been omitted.

In the form shown, the chain runs through a casing 4 and to one of the side walls of this casing I secure an oil box 5, here shown as having a cover 6 hinged thereto, and as being divided into a plurality of compartments by means of transversely extending partitions 7, by means of which a series of compartments is provided extending lengthwise of the chain and spaced apart in this direction.

Projecting from the box is a plurality of spouts indicated at 8, 9, 10 and 11. These

spouts are preferably spaced apart equal distances lengthwise of the chain, and are of different lengths, so that their ends form a substantially straight line. It is also preferable that each spout be connected to one of the compartments.

In operation, oil will be placed in each of the compartments of the box and, preferably, a porous substance 12 is also placed in the bottom of each box in such a way as to cover the inner end of the spout connected to that compartment. This porous material may conveniently be cotton waste, and its use is to cause the oil in the compartment to flow slowly through the spout connected to that compartment, so that the oil will drop or flow slowly from the end of the spout onto the chain beneath it. By spacing the spouts as shown, and by providing spouts of different lengths, the oil not only will drop onto different parts of the chain but will also be deposited substantially uniformly across the width of the chain. Of course, the spacing and lengths of spouts may be varied, as desired, to obtain the desired lubrication.

I claim:

1. In an oiling device for a chain, an oil box disposed above the chain to be oiled, and at one side thereof, and a plurality of spouts projecting from said box and spaced apart lengthwise of the chain with the end of each spout disposed over the chain, said spouts being of different lengths, whereby oil dropping from their ends will strike different portions of the chain.

2. In an oiling device for a chain, an oil box disposed above the chain to be oiled, and at one side thereof, a plurality of spouts projecting from said box and spaced apart lengthwise of the chain with the end of each spout disposed over the chain, said spouts being of different lengths, whereby oil dropping from their ends will strike different portions of the chain, and a porous substance in said box covering the inner ends of the spouts, for the purpose set forth.

3. In an oiling device for a chain, an oil box disposed above the chain to be oiled and at one side thereof, said box being divided into compartments spaced lengthwise of the

chain, a spout projecting from each compartment and having its end disposed over the chain, said spouts being of different lengths, whereby oil dropping from their ends will strike different portions of the chain.

4. In an oiling device for a chain, an oil box disposed above the chain to be oiled and at one side thereof, said box being divided 10 into compartments spaced lengthwise of the chain, a spout projecting from each compartment and having its end disposed over the chain, said spouts being of different lengths, whereby oil dropping from their ends 15 will strike different portions of the chain, and a porous substance in each compartment covering the inner end of the spout connected to that compartment, for the purpose set forth.

5. In an oiling device for a chain, an oil box 20 disposed above the chain to be oiled and at one side thereof, said box being divided into compartments spaced lengthwise of the chain, a spout projecting from each compartment and having its end disposed over the chain, 25 said spouts being of different lengths and equally spaced apart, with their ends forming a substantially straight line, for the purpose set forth.

6. In an oiling device for a chain, an oil box 30 disposed above the chain to be oiled, and at one side thereof, and a plurality of spouts projecting from said box and spaced apart lengthwise of the chain with the end of each spout disposed over the chain, said spouts 35 being of different lengths and equally spaced apart, with the ends forming a substantially straight line, for the purpose set forth.

7. In an oiling device for a wide chain, an oil box 40 disposed above the chain to be oiled, and a plurality of spouts projecting from the box and having their ends disposed over the chain and spaced apart substantially equal distances across the chain.

8. In an oiling device for a wide chain, an oil box 45 disposed above the chain to be oiled, a plurality of spouts projecting from the box and having their ends disposed over the chain and spaced apart substantially equal distances across the chain, and a porous substance 50 in said box covering the inner ends of the spouts, for the purpose set forth.

RICHARD F. DOW.
